UNITED STATES PATENT OFFICE.

WALTER P. MURPHY, OF NEW YORK, N. Y.

CORRUGATED SHEET-METAL CAR END.

1,398,643.

Specification of Letters Patent. Patented Nov. 29, 1921.

Original application filed March 6, 1916, Serial No. 82,423. Patent No. 1,309,484, dated July 8, 1919. Divided and this application filed June 10, 1919, Serial No. 304,429. Renewed May 28, 1921. Serial No. 473,318.

To all whom it may concern:

Be it known that I, WALTER P. MURPHY, a citizen of the United States, residing at New York, in the county of New York and State of New York, have invented certain new and useful Improvements in Corrugated Sheet-Metal Car Ends, of which the following is a specification.

My invention relates to a sheet metal end structure for railway cars, more particularly for box cars, and the primary object of the invention is to provide a car end structure composed of one or more metal sheets, preferably of a plurality of sheets, overlapped and secured together, said sheet or sheets formed with vertically disposed strengthening and rigidifying corrugations or projections so disposed as to afford a maximum reinforcement midway between the side walls of the car.

In a vertically corrugated sheet metal car end the corrugations serve as beams to transmit any cargo thrust to the car framing, and also, to a certain extent, as posts to carry the roof load. Both stresses are likely to be greatest near the vertical center line of the end. The portions of the end structure adjacent the side walls of the car are rigidified and strengthened by the corner posts and therefore do not require the reinforcement provided by the corrugations to the extent, at least, that the middle portion requires such reinforcement. In accordance with my present invention the middle portion of the end is formed with corrugations or ribs of maximum depth while the side portions of the structure are provided with corrugations of lesser depth. In order to facilitate the fabrication of the end structure it is made up of a plurality of sheets, each sheet having corrugations of the same depth but the corrugations of the middle sheet being deeper than those of the sheets on opposite sides thereof.

A further object is to provide a sheet metal end structure composed of a vertically corrugated end sheet or sheets occupying the middle portion of the end and flat metal sheets at the extreme sides of the end structure.

The invention consists of the new and improved constructions, arrangements and devices shown in the drawing hereto attached and to be hereinafter described and claimed

for carrying out the above stated objects and such other incidental objects as will be hereinafter referred to.

A preferred embodiment of the invention is shown in the drawing in which—

Figure 1 is an end view of the superstructure of a railway box car provided with a sheet metal end constructed in accordance with my invention.

Fig. 2 is a vertical sectional view on line 2—2 of Fig. 1.

Fig. 3 is a sectional plan, on a larger scale, taken on line 3—3 of Fig. 1, and

Fig. 4 is a fragmentary plan view of the end of the box car with the roof boards of the car removed.

Referring to the drawing, 10 designates one of the end sills of the car, 11, 11 the adjacent corner posts, 12, 12 the side plates, 13 the ridge pole of the roof and 14 the roof purlins.

The end structure is composed, in this embodiment of the invention, of seven sheets or strips of metal designated 15, 16, 16, 17, 17 and 18, 18 which are overlapped on vertical lines and joined together by means of rivets 19. The lower edges of the sheets are inturned to provide flanges 20 which are secured to the end sill by bolts 21 or other suitable fastening devices. In this preferred form of the invention the sheets 18, 18 at the sides of the end structure are flat, that is to say, are not corrugated and are formed on the outer vertical edges with flanges 22 secured to the corner posts 11 by bolts 23. The sheets 17, 17 are formed with vertically disposed corrugations 24 which are relatively shallow. The plates 16, 16 are formed with deeper corrugations 25 and the center plate 15 is formed with still deeper corrugations 26. The corrugations of each sheet are of the same cross sectional configuration.

The upper edges of the sheets are preferably bent over inwardly on lines corresponding to the slope of the car roof to provide flanges 27, 28, 28, 29, 29 and 30, 30, these flanges being secured together by rivets 31 to constitute a rigid member or structure which widens toward the side walls of the car for supporting the ridge pole 13 and purlins 14 and for giving rigidity to the upper portion of the end wall panel, this flange structure, in effect, taking the place of the

usual end plate of the car. The flanges 30 are secured to the side plates 12 by means of angle brackets 32.

This application is a division of application Serial No. 82,423, filed March 6, 1916 (patented July 8, 1919, as Patent No. 1,309,484).

I claim:

1. A sheet metal end structure for a rail-way car, comprising an end panel formed with a relatively deep vertical corrugation adjacent the vertical center line of the end and formed with a shallower vertical corrugation on either side of the same, said structure being provided at the top with in-turned flanges to support the roof of the car and at the bottom with in-turned flanges for attachment to the under frame of the car.
2. A sheet metal end structure for a rail-way car comprising a plurality of sheets secured together and formed with relatively deep vertical corrugations adjacent the vertical center line of the end, and with shallower vertical corrugations on either side of the same, said structure being provided at the top with in-turned flanges to support the roof of the car.
3. A sheet metal end structure for a railway car comprising a plurality of sheets of metal joined to each other along vertical lines, the side sheets being flat and the center sheet corrugated.
4. A sheet metal end structure for a rail-way car comprising a plurality of sheets of metal joined to each other along vertical lines, the side sheets being flat and the center sheet formed with vertical corrugations.
5. A sheet metal end structure for a rail-way car comprising a plurality of corrugated sheets overlapped on vertical lines and secured together and to the frame of the car, each corrugated sheet being formed with uniform vertical corrugations, those of the central sheets being deeper than those of the adjacent sheets.
6. A sheet metal end structure for a rail-way car comprising a central sheet and side sheets overlapping on vertical lines and secured to each other and to the frame of the car, said sheets being formed with vertical corrugations, uniform for each such sheet, those of the central sheet being deeper than those of the side sheets.
7. A sheet metal end structure for a rail-way car comprising a plurality of sheets, overlapped on vertical lines and secured together and to the frame of the car, and formed with a plurality of vertical corrugations which terminate within the edges of the sheet and extend substantially from the floor to the roof of the car, and which are deepest at the center portion and shallower adjacent the opposite edges of said struc-

ture, said sheets being formed along their upper edges with in-turned flanges to rigidify the upper margins thereof to support the roof of the car.

8. A sheet metal end structure for a rail-way car composed of a plurality of end sheets secured together along vertical lines comprising a sheet at the middle of the end formed with vertically disposed corrugations of equal depth and sheets on opposite sides of said sheet formed with vertical corrugations of lesser depth.

9. A sheet metal end structure for a rail-way car composed of a plurality of end sheets secured together along vertical lines comprising a sheet at the middle of the end formed with vertically disposed corrugations of equal depth, and sheets on opposite sides of said sheet formed with corrugations of the same depth in each sheet but of lesser depth than the corrugations of the middle sheet.

10. A sheet metal end structure for a rail-way car composed of a plurality of end sheets secured together along vertical lines comprising a sheet at the middle of the end formed with vertical corrugations of equal depth and a plurality of sheets on each side of the middle sheet formed with vertical corrugations, the corrugations of each sheet of the side sheets being of the same depth but those of the sheets nearer the side walls of the car being shallower than those of the sheets adjacent the middle sheet.

11. A sheet metal end structure for a rail-way car composed of a plurality of end sheets secured together along vertical lines and formed each with a plurality of substantially vertical corrugations, those of each sheet being of substantially uniform depth but those in the middle of the end being deeper than those at the sides thereof.

12. A sheet metal end structure for a rail-way car composed of a plurality of end sheets secured together along vertical lines and formed with a plurality of substantially vertical corrugations, those of each sheet being of substantially uniform depth, the corrugations of the sheet at the middle of the end being of maximum depth and those of the sheets between said middle sheet and each side wall being progressively shallower.

13. A sheet metal end structure for a rail-way car formed with a plurality of groups of substantially vertical corrugations, the corrugations of each group being of substantially the same depth but those of one group differing in depth from those of the other groups.

14. A sheet metal end structure for a rail-way car formed with a plurality of groups of substantially vertical corrugations, the corrugations of each group being of substantially the same depth, and the corrugations

100

105

110

115

125

130

of the group adjacent the vertical center line of the end being deeper than those of the groups at the sides thereof.

15. A sheet metal end structure for a rail-
5 way car formed with a plurality of groups of substantially vertical corrugations, the corrugations of the center group being of maximum depth and those of the groups on each side thereof progressively shallower.

10 16. A sheet metal end structure for a rail-
way car formed with a plurality of groups of substantially vertical corrugations, the corrugations of each group being of substantially the same depth and merging one into 15 the next to give a sinuous configuration in cross section, and the corrugations of one group differing in depth from those of other groups.

17. A sheet metal end structure for a rail-
20 way car formed with a plurality of groups of substantially vertical corrugations, the corrugations of each group being of substantially the same depth and merging one into 25 the next to give a sinuous configuration in cross section and the corrugations of the group adjacent the vertical center line of the end being deeper than those of the groups at the sides thereof.

18. A sheet metal end structure for a rail-
30 way car composed of a plurality of end sheets secured together, some of said sheets being formed with rigidifying corrugations and others being flat.

19. A sheet metal end structure for a rail-
35 way car composed of a plurality of end sheets joined together along vertical lines, the sheet at the middle of the structure being formed with rigidifying corrugations

and the sheets at the side walls of the car being flat.

20. A sheet metal end structure for a rail-
way car composed of a plurality of end sheets joined together along vertical lines, the sheet at the middle of the structure being formed with rigidifying vertical cor- 45 rugations and the sheets at the side walls of the car being flat.

21. A sheet metal end structure for a rail-
way car composed of a plurality of end sheets overlapped and secured together 50 along vertical lines, the center sheet being formed with corrugations of maximum depth, the sheets adjacent thereto with corrugations of lesser depth and the sheets at the extreme sides of the end being flat. 55

22. A sheet metal end structure for a rail-
way car composed of a plurality of end sheets overlapped and secured together along vertical lines, the center sheet being formed with corrugations of maximum 60 depth, the sheets adjacent thereto with corrugations of lesser depth and the sheets at the extreme sides of the end being flat, the upper and lower edges of said sheets being bent inwardly to provide for attachment of 65 the end to the frame members of the car.

23. A sheet metal end wall panel for a railway car provided with a plurality of groups of vertically disposed rigidifying projections, the projections of each group 70 being of substantially equal size and the groups of projections arranged so as to give the center portion of the panel greater strength and rigidity than the side portions thereof.

WALTER P. MURPHY.
